UNITED STATES PATENT OFFICE.

ROY B. SCROGGS, OF EUGENE, OREGON.

AEROPLANE.

1,250,033.

Specification of Letters Patent. Patented Dec. 11, 1917.

Application filed January 23, 1917. Serial No. 144,025.

To all whom it may concern:

Be it known that I, ROY B. SCROGGS, a citizen of the United States, residing at Eugene, in the county of Lane and State of Oregon, have invented new and useful Improvements in Aeroplanes, of which the following is a specification.

This invention relates to aeroplanes or flying machines of the heavier-than-air 10 class, and particularly to aeroplanes of the biplane type, the primary object of the invention being to provide a construction of machine designed to afford a high degree of flying efficiency with a minimum of air resistance.

A further object of the invention is to provide an aeroplane having a body portion and sustaining surface of novel form and construction, for the purpose described.

20 A still further object of the invention is to provide steering and stabilizing means of a simple character designed especially for use in connection with a machine of the construction disclosed.

25 With these and other objects in view, the invention consists of the features of construction, combination and arrangement of parts hereinafter fully described and claimed, reference being had to the accompanying drawings in which:

Figure 1 is a top plan view of an aeroplane or heavier-than-air flying machine embodying my invention.

Fig. 2 is a side elevation of the same.

35 Fig. 3 is a front elevation.

Fig. 4 is a rear elevation.

Fig. 5 is a vertical longitudinal section.

Fig. 6 is a horizontal transverse section on the line 6—6 of Fig. 5.

40 Fig. 7 is a diagrammatic perspective view showing a certain adjustment of the rudder planes of the steering gear.

Fig. 8 is a similar view showing a different adjustment thereof.

45 In carrying my invention into practice I provide an aeroplane or flying machine of the class described comprising a hollow body or nacelle 1, provided with a supporting surface comprising wings 2 and 3 respectively forming upper and lower supporting planes. The body may be mounted upon any ordinary or preferred construction of launching and alighting base 4.

55 The body 1 may be constructed in any suitable manner to secure lightness of weight with strength and durability, such

as of a wood or metal framework having a covering of fabric or sheet metal. The said body is of quadrangular pyramidal form, having its apex or reduced end forwardly 60 presented. The upper surfaces 5 of this body form a top or deck portion, while the side and bottom surfaces 6 and 7 thereof extend rearwardly with the surfaces 5 in diverging relation, as shown. At a suitable 65 point the body is provided with a cock pit or compartment 8 for the aviator and one or more passengers, and its widened rear portion 9 forms a compartment of requisite area to receive a motor 10 for driving the 70 propeller 11.

The planes 2 and 3 are of greatest length in the direction of flight of the machine, and are of triangular form, the side edges of the wings of these planes, which are widest at 75 their bases or rear edges, extend forwardly in converging relation and approximate at or adjacent to the reduced point or bow portion of the body 1. The planes are reinforced from the body and from each other 80 by suitable stays or braces 12 of a kind designed to afford requisite strength and rigidity with a minimum of resisting surface.

The wings or planes may be either 85 straight or curved, depending upon the contemplated angle of attack or angle of incidence, and other conditions, curved planes being preferably employed. The planes are so arranged with respect to the portions of 90 the surface of the body 1, as to give their maximum lifting effect at the point where the greatest weight comes, namely in rear of the transverse line of the cock pit, so as to provide for a correct and efficient coincidence of the center of gravity with the center of pressure for a reliable inherent 95 balancing action. By the form and construction of body and supporting surface disclosed, a machine is provided which in effect has the same general configuration and 100 minimum resistance to flight as a dart, thus allowing great speed to be obtained without a great expenditure of driving power, since the shape of the machine allows of the 105 use of material of very light weight without the sacrifice of structural strength, and also admits of the propulsion of the craft without great atmospheric resistance.

I also provide steering and stabilizing 110 means particularly adapted for use in conjunction with my improved type of machine.

This improved steering and stabilizing means comprises front and rear rudder planes 13 and 14, the plane 13 at least partaking of the general configuration of the machine structure, or being of triangular form. These planes are pivotally mounted for normal swinging movement on horizontal transverse axes 13' and 14', whereby the planes are coupled to the ends of a longitudinally extending rod or shaft 15. This rod or shaft extends through and is journaled in the body 1 for lateral rocking motion with a steering wheel or element 16 disposed within the cock pit 8. This steering wheel or element 16 is rigidly connected with the rod or shaft for the purpose of transmitting lateral rocking movements thereto, but is pivotally mounted, as at 17, for fore-and-aft tilting motions, the construction being such that the steering member and shaft may be tilted laterally in either direction as a unit or the steering member tilted backward or forward independently. The steering wheel is coupled by sets of cables 18 and 19, passing over suitable guides 20, with the respective rudder planes 13 and 14, whereby the said planes may be pivotally adjusted in opposite directions simultaneously on their axes, while they may also be adjusted simultaneously in the same direction by the lateral motions of the shaft in planes at right angles to their pivotal movements. It will thus be seen that by tilting the wheel the rudders may be vertically adjusted for ascent and descent and longitudinally balancing the machine, and that by turning the wheel and shaft in one direction or the other and simultaneously tilting the rudders to

desired angles of incidence the machine may be steered and balanced laterally, the control mechanism adapting the rudders to be operated in a simple and convenient manner to secure various combinations of movements for sensitive steering and balancing actions.

From the foregoing description, taken in connection with the drawings, the construction and mode of operation of my improved aeroplane will be readily understood, and it will be seen that the invention provides a machine of this character which will afford great strength and durability and maximum speed with comparatively low driving power. Also it will be seen that the invention provides a steering mechanism which is peculiarly adapted for use in connection with the improved means in providing rudders especially designed and arranged for coöperation with the supporting surfaces to give a wide range of flexibility in steering and controlling actions.

I claim:—

A flying machine including a hollow frusto pyramidal body having its apex forwardly directed, pairs of triangular wings arranged in superposed relation on opposite sides of the body and having their side edges converging forwardly toward the apex of the body, rudder planes arranged at the front and rear of the body, a longitudinally extending rock shaft on which said rudder planes are tiltably mounted, and means for rocking said shaft and also tilting said rudder planes.

In testimony whereof I affix my signature: ROY B. SCROGGS.
